UNITED STATES PATENT OFFICE.

EARL W. MORTER, OF WASHINGTON COURT HOUSE, OHIO.

RECEPTACLE-DISTRIBUTING DEVICE.

Application filed February 15, 1923. Serial No. 619,169.

To all whom it may concern:

Be it known that I, EARL W. MORTER, a citizen of the United States, residing at Washington Court House, in the county of

5 Fayette and State of Ohio, have invented certain new and useful Improvements in Receptacle-Distributing Devices, of which the following is a specification, reference being had therein to the accompanying drawing.

10 This invention relates to a receptacle distributing device and is in the nature of an improvement on the mechanism shown in Patent No. 1,420,936 granted to me June 27, 1922.

15 In canning factories and other places where receptacles are filled with commodities the empty receptacles are usually transferred from the warehouse or other source of supply to the filling machines by means

20 of a conveyor, which may be in the form of a track and along which receptacles may move by gravity or along which they may be impelled by suitable feeding devices, such as cables or other positively actuated devices.

25 It is frequently desirable to deliver the receptacles from a single main conveyor to two filling machines and, to accomplish this, branch conveyors are led from the main conveyor to the respective filling machines and a

30 suitable distributing device is interposed between the branch conveyors and the main conveyor. The filling machines frequently operate at a very high rate of speed and the distributing device must be of such a character that it will deliver a proper supply of

35 receptacles to each filling machine and it must therefore, operate at a high rate of speed and with great accuracy.

One object of the invention is to provide 40 a distributing device of this character which will be simple in its construction, positive in its operation and which may be driven at high speed.

A further object of the invention is to 45 provide such a device with improved means for controlling the discharge of receptacles to the respective branch conveyors; and in which the controlling means will be actuated through yieldable mechanism which will permit the driving mechanism to continue its 50 operation without injury to any part of the device in the event the movement of the controlling means is interrupted.

A further object of the invention is to 55 provide a device of this kind in which the distributing element can be shifted from one

position to the other without resistance from the receptacles in the main chute.

A further object of the invention is to provide a driving mechanism which will be 60 simple in its construction and operation and which will effectively operate the mechanism as a whole but will have a yieldable connection with the driven parts to permit of its continued operation in the event the 65 movement of the driven parts is interrupted.

Other objects of the invention will appear as the invention is described in detail.

In the accompanying drawings Fig. 1 is a top plan view of a device embodying my 70 invention; Fig. 2 is a front elevation of the same; Fig. 3 is an end elevation of the same; Fig. 4 is a section taken on the line 4—4 of Fig. 2; and Fig. 5 is a section taken on the line 5—5 of Fig. 1. 75

In these drawings I have illustrated one embodiment of my invention but it will be understood that this has been chosen for the purpose of illustration only and that the mechanism may take various forms without 80 departing from the spirit of the invention.

In the particular construction here illustrated I have shown the device as comprising a main frame 1 having at its upper end a main chute 2 and also having two diverging branch chutes 3 and 4. The main chute 2 in the present machine consists of a short passageway which is connected at its upper end with the main conveyor, shown at 5 in dotted lines in Fig. 5. The branch chutes 90 are adapted to be connected with the branch conveyors, which are not here shown, but which may be of any suitable character. These branch chutes may be of any desired construction but they are, in the present instance, provided in their inner and outer walls with openings through which a cut-off or controlling device may project to control the discharge of the receptacles therefrom. The upper ends of the branch chutes 95 are spaced some distance from the lower end of the main chute and a suitable connecting device is interposed between the branch chutes and the main chute and is movable from one position to another to alternately 100 connect the branch chutes with the main chute. This movable connecting device, or switch, may take various forms but, in the present machine, it comprises side walls 6

105 pivotally mounted at their lower ends near the upper ends of the outer walls of the respective branch chutes and connected one 110

to the other by cross bars or links 7, with which the side walls 6 are pivotally connected. Arranged between the side wall 6 and substantially parallel therewith is a partition 8 which is pivotally mounted at its lower end near the upper ends of the inner walls of the branch chutes, as shown at 9, and is pivotally connected at its upper end to the links 7, as shown at 10. This partition 10 divides the space between the side walls 6 of the connecting device into two passageways which are in permanent communication at their lower ends with the respective branch chutes 3 and 4 and which, in effect, form 15 movable extensions of those branch chutes. Because of the pivotal mounting of the several parts of the connecting device it can be swung from side to side so as to bring either 20 passageway into line with the main chute 2. Suitable means are provided for accurately 25 positioning the respective passageways with the main chute and, as here shown, each side wall 6 has an upwardly extending portion 11 arranged to engage the wall of the main chute and which serves as a stop to check 30 the movement of the connecting device when the adjacent passageway is in line with the main chute.

In order to control the passage of the receptacles through the branch chutes I have 35 provided a controlling device or cut-off 12 having parts 13 and 14 adapted to extend through the openings in the inner walls of the respective branch chutes and to close 40 the outlet ends of these chutes, so as to prevent the passage of the receptacles from the chute. The movement of this cut-off or controlling device is synchronized with the movement of the connecting device and it 45 is so arranged that the outlet of that branch chute which is connected with the main chute will be closed, thereby allowing only a predetermined number of receptacles to enter the branch chute. Further, this cut-off is so 50 arranged that when the predetermined number of receptacles have entered the branch chute the uppermost of said receptacles will support the following receptacle in the main chute and out of the path of the partition 55 10, so that the receptacle in the main chute will offer no resistance to the movement of the connecting device. This is important because if the lower surface of the lowermost receptacle in the main chute projects below 60 the bottom of the chute so that it will lie in the path of the upper end of the partition it is necessary for the partition to force this receptacle backward in order to pass the same and the receptacles in the main chute 65 are subjected to considerable pressure, either due to the weight of the following receptacles or to the action of the feeding mechanism thereon, and considerable resistance is thus offered to the movement of the connecting device. The controlling device or cut-off

may take various forms and may be actuated in various ways but, as here shown, it consists of a curved bar secured near the center thereof to the lower end of an arm 15 which is connected with and may, if desired, form 70 an extension of the partition 8 of the connecting device, so that the cut-off is maintained at all times in an exact predetermined position with relation to the connecting device. The cut-off bar is of such a length that 75 when in an intermediate position, with the partition 8 in a vertical position, both parts of the cut-off will be in inoperative positions and the outlets of both branch chutes will be unobstructed. Further, both parts, 13 80 and 14, of the cut-off bar are provided with abutments 16 which, in the event that one or both of the branch chutes are full of receptacles, will engage one of said receptacles and interrupt the movement of the cut-off 85 and of the connecting device. The mechanism may be operated from any suitable source of power and through any suitable driving mechanism but it is desirable that this driving mechanism shall be yieldably 90 connected with the driven parts so that the driving mechanism may continue its movement without injury to any part of the mechanism in the event the movement of the driven parts is interrupted, due either 95 to the fact that either one or both of the branch chutes are full of receptacles and the cut-off cannot enter the same or to the wedging of a receptacle between the partition 10 and the side wall of the main chute, which 100 may happen if the receptacles are moving through the main chute intermittently. As here shown the mechanism is driven from a belt wheel 17 which may be connected with any suitable source of power and which is 105 mounted on a shaft 18 provided with a crank 19 with which is connected a pitman or driving rod 20. This pitman is connected at its other end with a bracket 21 which is rigidly secured to an actuating rod 22. The 110 actuating rod 22 is slidably mounted in bearings 23 mounted on the main frame 1 and is slidably mounted between said bearings in a bearing 24 pivotally mounted on an actuating arm or lever 25 which is pivotally mounted between its ends at 9 on the main frame 1 and is pivotally connected at its upper end with the links 7 of the connecting device, as shown at 26, and is pivotally connected at its lower end with the arm 15 of the cut-off, as shown at 27. Springs 28 are coiled about the rod 22 on the respective sides of the bearing 24 and are confined between that bearing and stops or collars 29 rigidly secured to the rod. The tension of the springs 28 is such that they will transmit the movement from the rod to the driven parts of the mechanism with but little yielding movement so long as these parts are free 120 to move in a normal manner, but the length 125 130

of the springs is such that, in the event that the movement of the driven parts should be interrupted, the springs will compress sufficiently to permit the driving mechanism to complete its movement without injury to any part of the mechanism.

The operation of the device will be readily understood from the foregoing description of the several parts thereof and it will be apparent that with the connecting device in the position shown in Figs. 2 and 5, the part 14 of the cut-off will extend across the branch chute 4 and this chute will fill with receptacles. In the present instance it will receive five receptacles, and the uppermost receptacle will support the lower receptacle in the main chute out of the path of the partition 8 of the connecting device. When the movement of the driving rod 22 is reversed the connecting device will be shifted to connect the other branch chute, 3, with the main chute and at the same time the part 14 of the cut-off will be withdrawn from the branch chute 4 to permit the receptacles to be discharged therefrom by gravity and the part 13 of the cut-off will enter the branch chute 3 before the partition 8 has cleared the lower end of the main chute and consequently before a receptacle can enter the branch chute 3. The arrangement of the driving mechanism is such that there will be a dwell at the end of each movement of the actuating rod 22, this being due to the passage of the crank 19 across its central position, and this dwell will be of sufficient length to permit the branch chute, which is then connected with the main chute, to fill with receptacles before reverse movement is imparted to the connecting device. If, for any reason, the passage of the receptacles from one of the branch chutes should be interrupted, as, for example, if the operation of one of the filling machines is temporarily discontinued, the abutment 16 of the cut-off 45 will engage one of the receptacles in that chute and will interrupt the movement of the cut-off and consequently of the connecting device, but the connection between the driving mechanism and the operating lever 25 will yield sufficiently to permit the rod 22 to complete its movement and consequently the passage of the receptacles through the other branch chute will continue in the same manner as if the receptacles were being delivered from the first mentioned branch chute in a normal manner. Should both branch chutes be full of receptacles the cut-off will be held in an intermediate position between the two chutes, both springs 28 55 then yielding alternately to permit the rod 22 to continue its movement. As soon as the delivery of the receptacles from one or both of the branch chutes is resumed the mechanism will begin to operate in a normal manner. If the receptacles are feeding along

the main conveyor to the distributing device intermittently there is a possibility that the movement of the connecting device from one position to the other will cause the partition 8 to engage a receptacle just as it leaves the main chute and for the receptacle to thus become wedged between the partition and the side wall of the main chute. If this happens the movement of the connecting device is, of course, interrupted but as soon as the movement of the actuating rod 22 has been reversed the connecting device will be moved in the opposite direction and the wedged receptacle released and permitted to enter the branch chute and the normal operation of the distributing device will be again resumed.

While I have shown and described one embodiment of my invention I wish it to be understood that I do not desire to be limited to the details thereof as various modifications may occur to one skilled in the art.

Having now fully described my invention what I claim as new and desire to secure by Letters Patent, is:

1. In a mechanism of the character described, a main chute, two branch chutes, means to cause said branch chutes to be alternately connected with said main chute; a cut-off pivotally mounted adjacent to the upper ends of said branch chutes comprising a movable member extending downwardly between said branch chutes, parts carried by said member and arranged to move into the respective branch chutes, through the inner sides thereof, to control the outlets of said chutes, and means for actuating said movable member in synchronism with the first mentioned means.

2. In a mechanism of the character described, a main chute, two branch chutes, means to cause said branch chutes to be alternately connected with said main chute, a cut-off pivotally mounted adjacent to the upper ends of said branch chutes comprising a movable member extending downwardly between said branch chutes, parts carried by said member and arranged to move into the respective branch chutes, through the inner sides thereof, to control the outlets of said chutes, and yieldable means for actuating said movable member in synchronism with the first mentioned members.

3. In a mechanism of the character described, a main chute, two branch chutes, means to cause said branch chutes to be alternately connected with said main chute, a single controlling device pivotally supported adjacent to the upper ends of said branch chutes and extending downwardly between said branch chutes for movement toward and from the same and having parts adapted to enter the respective branch chutes to control the outlets thereof, said device being of such a length that when it is

- in an intermediate position both of said parts will be in inoperative positions with relation to the respective branch chutes, and means for actuating said device.
- 5 4. In a mechanism of the character described, a main chute, two branch chutes, means to cause said branch chutes to be alternately connected with said main chute, a single controlling device pivotally supported adjacent to the upper ends of said branch chutes for movement toward and from the same and having parts adapted to enter the respective branch chutes to control the outlets thereof, each of said parts 10 having an abutment to engage an article in one of said branch chutes and interrupt the movement of said device when said branch chute is full of articles, and yieldable means for actuating said devices.
- 10 5. In a mechanism of the character described, a main chute, two branch chutes, a movable connecting device having two passageways arranged to connect the respective branch chutes alternately with said main chute, and means to actuate said connecting device.
- 15 6. In a mechanism of the character described, a main chute, two branch chutes, a movable connecting device having two passageways communicating with the respective branch chutes and movable alternately into communication with said main chute, and means to actuate said device.
- 20 7. In a mechanism of the character described, a main chute, two branch chutes, a connecting device having two passageways forming extensions of the respective branch chutes and movable alternately into communication with said main chute, and means to actuate said device.
- 25 8. In a mechanism of the character described, a main chute, two branch chutes, a movable connecting device having two passageways communicating with the respective branch chutes and movable alternately into communication with said main chute, said device having means to properly position the respective passageways with said main chute, and means for actuating said device.
- 30 9. In a mechanism of the character described, a main chute, two branch chutes, a movable connecting device comprising outer walls pivotally mounted at their lower ends near the upper ends of the outer walls of the respective branch chutes, a partition arranged between said outer walls to divide said device into two passageways, said partition being pivotally mounted near the 35 upper ends of the inner walls of said branch chutes, means for connecting said partition and said walls one with the other, and means for moving said device to cause said passageways to move alternately into communication with said main chute.
- 40 10. In a mechanism of the character described, a main chute, two branch chutes, a movable connecting device comprising outer walls pivotally mounted at their lower ends near the upper ends of the outer walls of the respective branch chutes, a partition arranged between said outer walls to divide said device into two passageways, said partition being pivotally mounted near the 45 upper ends of the inner walls of said branch chutes, means for connecting said partition and said walls one with the other, means for moving said device to cause said passageways to move alternately into communication with said main chute, and a part connected with each of said side walls to limit the movement of the same toward said main chute.
- 50 11. In a mechanism of the character described, a main chute, two branch chutes, a movable connecting device having two passageways arranged to connect the respective branch chutes alternately with said main chute, means to actuate said connecting device, and means synchronized with said connecting device for controlling the outlets of said branch chutes.
- 55 12. In a mechanism of the character described, a main chute, two branch chutes, a movable connecting device having two passageways arranged to connect the respective branch chutes alternately with said main chute, means to actuate said connecting device, and means synchronized with said connecting device to close the outlet of that 60 branch chute which is connected with said main chute.
- 60 13. In a mechanism of the character described, a main chute, two branch chutes, a movable connecting device having two passageways arranged to connect the respective branch chutes alternately with said main chute, means to actuate said connecting device, controlling mechanism having parts adapted to enter the respective branch 65 chutes to close the outlets thereof, and means for causing said parts to enter the respective chutes when said chutes are connected with the main chute.
- 70 14. In a mechanism of the character described, a main chute, two branch chutes, a movable connecting device having two passageways arranged to connect the respective branch chutes alternately with said main chute, means to actuate said connecting device, a controlling device having parts movable into and out of the respective branch chutes, and means for actuating said device in timed relation to the movement of said connecting device.
- 75 15. In a mechanism of the character described, a main chute, two branch chutes, a movable connecting device having two passageways communicating with the respective branch chutes and movable alternately into communication with said main chute.

into communication with the main chute, means for actuating said device, and parts connected with said connecting device and movable into the respective branch chutes 5 to control the outlets thereof.

16. In a mechanism of the character described, a main chute, two branch chutes, a connecting device comprising a partition dividing the same into two passageways 10 which communicate with the respective branch chutes, means for actuating said connecting device to move said passageways alternately into communication with said main chute, and a cut-off connected with 15 said partition and having parts adapted to enter the respective branch chutes to control the outlets thereof.

17. In a mechanism of the character described, a main chute, two branch chutes, a 20 connecting device comprising a partition dividing the same into two passageways which communicate with the respective branch chutes, means for actuating said connecting device to move said passageways 25 alternately into communication with said main chute, a cut-off connected with said partition and having parts adapted to enter the respective branch chutes to control the outlets thereof, each part of said cut-off having an abutment at its outer end.

18. In a mechanism of the character described, a main chute, two branch chutes, a movable connecting device having two 35 passageways arranged to connect the respective branch chutes alternately with said main chute, an actuating mechanism for said connecting device, said actuating mechanism being arranged to provide a dwell at the end of each movement of said connecting 40 device.

19. In a mechanism of the character described, a main chute, two branch chutes, a movable connecting device having two 45 passageways arranged to connect the respective branch chutes alternately with said main chute, a cut-off having parts adapted to enter the respective branch chutes, an actuating rod connected with both said connecting device and said cut-off, and means 50 for imparting movement to said actuating rod.

20. In a mechanism of the character described, a main chute, two branch chutes, a 55 movable connecting device having two passageways arranged to connect the respective branch chutes alternately with said main chute, a cut-off having parts adapted

to enter the respective branch chutes to control the outlets thereof, a lever operatively connected with said connecting device and 60 with said cut-off, and an actuating device yieldably connected with said lever.

21. In a mechanism of the character described, a main chute, two branch chutes, a 65 movable connecting device having two passageways arranged to connect the respective branch chutes alternately with said main chute, a cut-off having parts adapted to enter the respective branch chutes to control the outlets thereof, a lever operatively 70 connected with said connecting device and with said cut-off, a bearing carried by said lever, an actuating rod slidably mounted in said bearing, stops secured to said rod on opposite sides of said bearing, springs confined between the said bearing and the respective stops, and means for imparting reciprocal movement to said actuating rod.

22. In a mechanism of the character described, a main chute, two branch chutes, a 80 movable connecting device having two passageways arranged to connect the respective branch chutes alternately with said main chute, a cut-off having parts adapted to enter the respective branch chutes to control the outlets thereof, a lever operatively connected with said connecting device and with said cut-off, a bearing carried by said lever, an actuating rod slidably mounted in said bearing, stops secured to said rod on 85 opposite sides of said bearing, springs confined between the said bearing and the respective stops, a driving shaft having a crank, and a pitman connecting said crank with said actuating rod.

23. In a mechanism of the character described, a main chute, two branch chutes, a connecting device comprising a part dividing the same into two passageways, means for actuating said device to move said passageways alternately into communication with said main chute, means synchronized 100 with said connecting device to close the outlets of said branch chutes, said means being so arranged that when a predetermined 105 number of receptacles have entered one of said branch chutes the lowermost receptacle of the main chute will be supported out of the path of said part of said connecting device.

In testimony whereof, I affix my signature hereto.

EARL W. MORTER.
